UNITED STATES PATENT OFFICE

GAETANO LANZA, OF BOSTON, MASSACHUSETTS.

ENGINE-INDICATOR.

No. 902,586.

Specification of Letters Patent.

Patented Nov. 3, 1908.

Application filed October 6, 1906. Serial No. 337,730.

To all whom it may concern:

Be it known that I, GAETANO LANZA, a citizen of the United States, and resident of Boston, in the county of Suffolk and State of Massachusetts, have invented new and useful Improvements in Engine-Indicators, of which the following is a specification.

My invention relates to power indicating apparatus and to the manufacture of continuous indicators for use with fluid pressure engines; the object of my invention is to provide a continuous indicator which shall accurately feed a continuous strip of paper in one direction at velocities always strictly proportionate and correspondent to the velocities of the reciprocating parts of the engine whereby a continuous record of the pressure cycle of the engine may be made through as many consecutive double strokes of its reciprocating parts as may be desired. Theoretically the continuous engine indicator, wherein the strip of paper, instead of being reciprocated as with the ordinary steam engine indicator, is fed continuously in one direction in correspondence with the movement of the reciprocating parts of the engine, is an instrument far superior to the steam engine indicators which have been, so far as I know, almost universally employed, because the ordinary indicator card exhibits a diagram of pressure per square inch in the cylinder of the engine at each point in the travel of the piston during only one rotation of the crank. When this diagram has been taken, the indicator card is removed and another substituted. Assuming that one card is taken every three minutes and that the engine is making 300 revolutions per minute, it follows that only one card is obtained for every 900 revolutions of the engine, and, in estimating the power exerted by the engine, it is to be assumed that the other 899 strokes, if indicated, would show a pressure diagram identical with the one taken. Such a mode of procedure might be justifiable and such an assumption correct, if the load on the engine was known to be constant; but this assumption is far from being in accord with the actual facts when the load of the engine is variable. The error which follows such a method of procedure would be removed if all the 900 cards were taken and would be decreased if a larger percentage of the 900 possible indicator cards were taken. Hence fol-

lows the need of a mechanically accurate continuous indicator. In order to insure the correct operation of a continuous indicator, the speed of that part of the paper strip upon which the record is made, must be at all times truly proportional and correspondent to that of the point on the reducing motion or on the moving part of the engine from which the motion is taken and this correspondence must not be impaired or destroyed by slippage or back-lash or any other cause.

My improved continuous indicator herein to be described involves the use of a combination of mechanisms by means of which the continuous motion of a drum which determines the speed of the paper strip upon which the record is made shall be derived directly from some point on the reducing motion or some moving part of the engine as the piston, piston rod, or cross head, not only for the forward but also for the backward stroke of the engine. Moreover, in my improved continuous indicator the motion of the paper strip for both the forward and backward stroke of the engine is derived directly, and for neither stroke is it derived by means of a spring or other secondary source of movement.

In the drawings hereto annexed which illustrate an embodiment of my invention, Figure 1 shows an indicator in side elevation; Fig. 2 shows the operating clutches for the paper drum motion, partly in elevation and partly in cross section, on the line 2—2 of Fig. 3; Fig. 3 is a cross section of Fig. 2 on the line 3—3; Fig. 4 is a cross section of Fig. 1 on the line 4—4 looking upward; Fig. 5 is a cross section taken at Fig. 1 along the line 5—5 looking upward; Fig. 6 is a view, partly in cross section, showing the dead point marking apparatus; Fig. 7 is a view, partly in cross section and partly in elevation, showing the driving mechanism for the winding up roll; and Fig. 8 is a horizontal cross sectional view on the line 8—8, Fig. 1 looking downward showing the pressure roll and the releasing mechanism therefor.

The general arrangement of the indicator mechanism is shown in Fig. 1. The swinging arm G pivoted to any suitable support (not shown) at K, is a type of reducing motion which derives its reciprocating movement from some point on the reciprocating parts of the engine, and as this mechanism is

very familiar to engineers, the connections between the reducing arm G and the engine, are not shown. The cycle of movement of the reciprocating parts of the engine is transmitted to the indicator mechanism by means of the cords g and g' whereof g is secured at one end to the rotatively reciprocating clutch E and g' is secured at one end to the rotatively reciprocating clutch F, the cord g' passing over the pulley g'; both cords are secured to the reducing motion at g².

The indicator mechanisms are mounted in a frame which is composed of metal plates A, A', A², A³, and columns L, L, L. The master drum D whereon the paper strip P is carried while the indicator diagram is being made in the usual manner by the scribing device C' actuated by pressure in the indicator cylinder G, is mounted upon the shaft D' which passes through the axes of the rotatively reciprocating clutches E, F, and is supported upon a bracket or step P'. The clutches E, F are so constructed that when they are rotated by the cords g, g' in response to the movement of the point g² on the reducing motion to which the ends are attached they grip fast to the shaft D' to turn it and the master drum D in correspondence to the movement of the reciprocating parts of the engine, the clutch E serving for this purpose when the arm G is moving toward the right (Fig. 1) and the clutch F serving this purpose when the point g² is moving toward the left. As the cord g' passes over the pulley g' before reaching the clutch F, it is plain that the movement of the arm G toward the left produces a movement of the lower part of the cord g' toward the right and consequently actuates the clutch F. Each of the clutches E, F is provided with a return spring which, when the direct draft of the actuating cord is intermittent, returns the clutch and holds the cord g, or g', stretched taut and in readiness for active operation upon the clutch. Thus, as the master drum D is given a movement always in one direction whether the reciprocating parts of the engine are in forward or backward stroke and this movement of the master drum D is always in harmony and correspondence with the varying velocity of the reciprocating parts of the engine. Various specific forms and constructions of alternately operative clutches may be adopted or contrived; in Figs. 2 and 3 I have shown a form which operates satisfactorily. The standards E', F' are secured to the frame plate A², the shaft D' passing through both standards which are in alinement for this purpose. The construction of the two clutches is the same so that a description of the clutch E will suffice for both. The clutch pulley e' is grooved at e² for the reception of the cord g and this pulley is sleeved at e³ to turn upon the extension e⁵ of the standard and on the threaded end of which is secured

the nut e⁶ which serves to hold the moving parts of the clutch in assembled position. The sleeved disk e⁹ slips over the extension e⁵ and sleeve e⁸ and to this sleeved disk is secured one end of the coiled spring e³, said spring being secured at its other end to the outer flange e⁷ of the pulley e'. The clutch E itself is secured to the shaft D' as by a set screw e. Secured to or integral with the body of this clutch there are provided the blocks e¹⁰ between the inclined sides of which and the periphery of the clutch pulley e', the clutch rollers e⁴ operate, being constantly pressed toward a position of engagement by the spring pins e¹¹. Thus, when by the action of the cord g the clutch pulley e' is rotated in one direction, the clutch members including the clutch rolls e⁴ bring the part E into substantial unity with the pulley e' and when the draft of the cord g is relaxed, the spring e³ returns the pulley e', the rolls e⁴ being released by this reverse movement. In Fig. 2 the corresponding pulley f' grooved at f² and the set screw f for securing the member F to the shaft D' are indicated.

Referring to Figs. 1 and 4 where the mechanism directly relating to the movement of the paper strip is illustrated, H is a paper supply roll which rotates to deliver paper as required, being actuated by the draft of the paper strip itself. The paper strip P passes from the supply roll H over the movably mounted pressure roll I, thence around the master drum D between it and the supplemental pressure or guide roll R and thence to the drawing off or receiving roll J, against which a pressure block S is made to bear by the light spring s' mounted at s². The rotative movement of the master drum D is predetermined by the connections through the clutches E and F to the reducing motion and the essential requirement is that the paper strip shall, while in contact with the master drum D, rest on the surface thereof without slipping. The direct connections of the clutches E and F above described with the reducing motion without the employment of any springs except those which return the clutch pulleys to the initial point of their operation, and without any intervening gears or other mechanical connections which may involve loose motion or back-lash, insure the proper correspondence of the movement of the drum D with the movement of the reciprocating parts of the engine, so that the operations of the mechanism remaining to be described are devoted to the correct transmission of the movement of the drum D to the paper strip P. In the first place, it is advisable that the surface of the master drum D and of the pressure roll I be such that considerable friction of position exists between it and the paper strip P. This may be accomplished so far as relates to the drum D, by slightly corrugating its surface. The

pressure roll I and guide roll K assist materially in maintaining proper intimacy of contact between the strip and the drum. The receiving or drawing off roll J derives its motion from the shaft D' through the train of gears d , d' , d^2 , d^3 (see Figs. 1 and 7). These gears are so proportioned that the movement of the receiving roll shaft J' always tends to give the roll J or the paper strip wound upon it a surface speed in excess of the surface speed of the master drum D. On the shaft j' the heads J', J² are replaced and the spring seat J⁴ is secured to the shaft j'; between this spring seat and the loose head J² there is provided the coiled spring J³. Thus the connection between the shaft j' and the roll J is frictional and not positive and this frictional connection is so adjusted that the friction of position of the paper roll P upon the master drum D entirely dominates the situation, so that the paper strip is allowed to pass to the roll J only as it is delivered by the movement of the master drum D; nevertheless the constant tendency of the roll J to run away, as it were, from the master drum D, keeps the paper strip P under proper tension and prevents it from loosening its grip upon the master drum D.

In order to start and stop the paper strip, the mechanism shown in Figs. 1, 5 and 8 is provided. A shipper T in the form of a bell crank lever is pivoted concentrically with the shaft D' and carries a stud for the double gear d' , d^2 , the spring t normally holds the shipper lever T against the stop t' and the gears d^2 , d^3 out of engagement.

The pressure roll I is mounted to turn in the frame Q shown in cross section in Fig. 8 and the said frame travels in slides W of which one is shown in Fig. 8, the other at the opposite end of the pressure roll I being similar to the one shown in the said figure. A pin Q² sliding in a guide Q' is mounted on the back side of the frame Q and a spring Q⁴ constantly urges the frame and the roll I carried thereby toward the master roll D. The link U is pivotally connected to the lever T and the rocker U', this rocker being secured to a vertical rock shaft U² which is pivotally mounted in the plates A, A' of the frame. One end of the rocker U' constitutes the finger U³ which is so proportioned that it is adapted to engage with the upright part of the frame Q. When the lever T is moved to disengage the gears d' , d^2 , the rocker U' is actuated by the link connection U so that the finger U³ pushes the frame Q and the roller I carried thereby away from the master roll D and thus relieves the strip of paper from pressure between the rolls previously exerted by the spring Q⁴. Thus, when the indicator is started, the shipper T is moved so as to bring the gears d^2 , d^3 into mesh and at the same time to draw the pressure roll I with the paper strip into contact with the master

drum D, and the steam connections of the indicator being open, a continuous diagram is made so long as the shipper T is held in this position. When it is desired to interrupt the action of the indicator, the shipper T is released and the spring t simultaneously disengages gears d^2 , d^3 and moves pressure roll I away from the master drum D. The movement of the drawing off roll J ceases and although the movement of the master drum D continues, the paper strip is slackened so that no more of the strip is drawn from the supply roll H.

In making such a continuous indicator diagram it is highly advisable to have the points on the diagram which correspond to the dead points in the movement of the engine accurately marked. For this purpose I provide the marker M which in this case is a pointer secured to and operated by the armature of an electro-magnet M'. This electro magnet is included in a suitable electric circuit (not shown) whereof the closing terminals are at N, N', these being situated so that the circuit will be closed by the action of the stud G' on the arm G. By means of a screw and slot or equivalent devices as shown at N², the position of these terminal circuit closers may be accurately adjusted so that the circuit of the magnet M' shall be closed simultaneously with the occurrence of dead point in the movement of the engine and the armature point M will then make its mark upon the paper strip P so that the points on the diagram which correspond to the end of one stroke and the beginning of another, may easily be determined. The operation of the mark M cannot in any way interfere with the proper movement of the paper strip because the impress of the marker is made at the instant when the paper strip is substantially at rest.

By means of an indicator apparatus such as above described wherein the clutch connections are directly to the reducing motion so that backlash is avoided, and where the movement of the master drum carrying the paper strip is imparted to the strip without slip or interruption, an accurate continuous indicator diagram can be produced which is limited in length only by the length of the paper strip which can be carried by the instrument.

What I claim and desire to secure by Letters Patent, is:

1. In a fluid pressure engine indicator, a master drum, its shaft, two independent alternately operative devices to drive the drum shaft continuously in one direction, a connection from a reciprocating part of the engine to each of said shaft driving devices to positively operate both shaft driving devices in alternation, means for supplying paper to the master drum, and diagram tracing devices.

2. In a fluid pressure engine indicator, a master drum, its shaft, two independent alternately operative clutches to drive the drum shaft continuously in one direction, a connection from a reciprocating part of the engine to each of said clutches to positively operate both clutches in alternation, means for supplying paper to the master drum, and diagram tracing devices.
- 10 3. In a fluid pressure engine indicator, a master drum, its shaft, two rotative clutches, a clutch actuator positively controlled by and moving in conformity with the reciprocating parts of the engine, positive connections directly from said actuator to said clutches to advance the clutches alternately, each clutch being set to grip the drum shaft when turning in response to said action, both clutches to rotate the shaft in the same direction, means for supplying a paper strip to the master drum and devices to trace the pressure diagram.
- 15 4. In a fluid pressure engine indicator, a master drum, its shaft, two rotative clutches, each comprising a return spring, a clutch actuator positively controlled by and moving in conformity with the reciprocating parts of the engine and positive connections directly from said actuator to both of said clutches to advance the clutches alternately, each clutch being set to grip the drum shaft when turning in response to said action, both clutches to rotate the shaft in the same direction, means for supplying a paper strip to the master drum and devices to trace the pressure diagram.
- 20 5. In a fluid pressure engine indicator, a master drum, its shaft, two rotative clutches, a clutch actuator positively controlled by and moving in conformity with the reciprocating parts of the engine, cords positively secured to the rotative clutches and passing therefrom to the said actuator, one of said cords being carried over a pulley and thence to said actuator, to advance the clutches alternately, each clutch being set to grip the shaft when turning in response to the draft of the cord, both clutches to rotate the shaft in the same direction, means for supplying a strip to the master drum, and devices to trace the pressure diagram.
- 25 6. In a fluid pressure engine indicator, a master drum, its shaft, two rotative clutches each comprising a return spring, a clutch actuator positively controlled by and moving in conformity with the reciprocating parts of the engine, cords positively secured to the rotative clutches and passing therefrom to the said actuator, one of said cords being carried over a pulley and thence to said actuator, to advance the clutches alternately, each clutch being set to grip the shaft when turning in response to the draft of the cord, both clutches to rotate the shaft in the same direction, means for supplying a paper strip to the master drum, and devices to trace the pressure diagram.
- 30 7. In a fluid pressure engine indicator, a master drum and means to rotate said drum in one direction in constant correspondence with the movement of the reciprocating parts of the engine, a paper supply roll, a pressure roll, means to press the same against the master drum, a receiving roll, a spindle therefor, geared driving connections from the master drum to the spindle of the receiving roll, speeded to give the receiver roll a surface speed in excess of that of the master roll, and frictional connection between the receiving roll and said spindle, and pressure indicating devices to trace the diagram upon a strip carried by the master drum.
- 35 8. In a fluid pressure engine indicator, a master drum and means to rotate said drum in one direction in constant correspondence with the movement of the reciprocating parts of the engine, a paper supply roll, a pressure roll, means to press the same against the master drum, a receiving roll, its spindle, a driving gear therefor, speeded to give the receiver roll a surface speed in excess of that of the master drum, and friction connections between the receiving roll and its spindle, means to release the receiving roll from its driver, and pressure indicating devices to trace the diagram upon a strip carried by the master drum.
- 40 9. In a fluid pressure engine indicator, a master drum, and means to rotate said drum in one direction in constant correspondence with the movement of the reciprocating parts of the engine, a paper supply roll, a pressure roll, means to press the same against the master drum, a receiving roll, a driver therefor, speeded to give the receiver roll a surface speed in excess of that of the master drum, and friction connections between the receiving roll and its driver to maintain excess draft from the receiving roll to the master drum, means to simultaneously release the receiving roll from its driver and the pressure roll from the master drum, and pressure indicating devices to trace the diagram upon a strip carried by the master drum.
- 45 10. In a fluid pressure engine indicator, diagram tracing devices, means to move a paper strip in one direction in correspondence with the movement of the reciprocating parts of the engine, a strip marker, a reciprocating member in harmony with the reciprocating parts of the engine, and connections between said reciprocating member and the marker to actuate the marker simultaneously with the occurrence of dead point in the movement of the engine.
- 50 11. In a fluid pressure engine indicator, diagram tracing devices, means to move a paper strip in one direction in correspondence with the movement of the reciprocating parts of the engine, a strip marker, an elec-

tro-magnet to actuate the marker, a reciprocating member moving in harmony with the engine, contact points controlled by said reciprocating member, said contact points being set to determine the circuit closure of the magnet simultaneously with the occurrence of dead point in the movement of the engine.

Signed by me at Boston, Massachusetts,
